UNITED STATES PATENT OFFICE.

THOMAS JOHN FLANIGAN, OF BUTTE CITY, MONTANA TERRITORY.

DUMPING-CART.

SPECIFICATION forming part of Letters Patent No. 358,192, dated February 22, 1887.

Application filed August 6, 1886. Serial No. 210,216. (No model.)

To all whom it may concern:

Be it known that I, THOMAS JOHN FLANIGAN, of Butte City, in the county of Silver Bow and Territory of Montana, have invented a new and Improved Dump-Cart, of which the following is a full, clear, and exact description.

My invention relates to the construction of a body for that class of carts commonly called "dump-carts," the object of the invention 10 being to provide a cart-body which will successfully withstand the wear and tear incident to the carting of minerals and stones, but which shall be so constructed that the tail-board may be readily removed when it is desired to dump 15 the load carried by the cart.

Reference is to be had to the accompanying drawings, forming a part of this specification, in which similar figures of reference indicate corresponding parts in all the views.

20 Figure 1 is a side view of my improved form of cart-body. Fig. 2 is a view of the rear end of the same. Fig. 3 is a longitudinal sectional view taken on the line $\alpha\alpha$ of Fig. 2; and Fig. 4 is a detail view illustrating the arrangement 25 of one of the mortises in the rear cross-bar, the tail-board bolt being shown as in position within the mortise, but as removed from the tail-board.

The frame proper of the cart-body consists 30 of a forward cross-bar, 10, sills 11, that are secured thereto in any manner desired, intermediate floor-beams, 12, and a rear cross-bar, 13, which cross-bar is made of iron and is rigidly connected to the sills and the intermediate 35 beams, as clearly shown in the drawings. In order that the rigidity and stability of the body may be increased, I arrange auxiliary sills 14 beneath the sills 11, and the extending ends of these sills 14 are bound with metal 40 bands 15. As best shown in Fig. 2, the rear cross-bar, 13, extends beyond the outer faces of the sills 11, and to these extending ends I secure bracing or stay irons 16, that are bent to the form of a triangle, the base of which is 45 bolted to the cross-bar 13, while the outwardly flaring sides 17 serve as the support for the side-boards 18 of the wagon-body. The forward end of the cart consists of a board, 19, that is held to the forward cross-bar, 10, by 50 means of bolts which are secured to the inner face of the board and pass through the cross-bar 10, as illustrated. The side-boards 18 are

held to the board 19 by means of U-bolts 20, said bolts being secured to the outer faces of the side-boards, but being so arranged that 55 their extending ends will pass through the board 19, there to be engaged by nuts 21, as illustrated. The side-boards and the forward end-board, 19, are bound by metallic strips or bands 22 and 23.

60 The tail-board 24 is protected by facing or wear plates 25 and 26, the plate 25 being secured to the upper edge of the board, while the plate 26 serves as a protection for the lower edge thereof; and in order that the board may 65 be held from checking or splitting, I pass bolts 2 through the body of the board, and the heads of the bolts 2 are elongated and flattened and have their inner faces rounded off, as shown at 3 in Fig. 3. Elongated slots or mortises 4 70 are formed in the cross-bar 13 in position so that the elongated heads of the bolts 2 will enter the slots when the tail-board is placed in position at the rear end of the cart.

In order that the accidental displacement of 75 the tail-board may be prevented, I provide circular retaining-irons 5, which are secured to the side-boards 18 and arranged so that their extending ends will pass through apertures 6, formed in the tail-board, the ends of the retaining-irons being slotted to receive pins 7, that are connected to the tail-board by chains 8. Handles 27 are connected to the outer face of the tail-board by means of U-bolts 9.

80 In addition to the supports described as being arranged in connection with the side-boards 18, I provide each of said side-boards with two or more bolt-shanked straps, 28, said straps being bolted to the inner faces of the boards and their bolt-shanks being arranged 90 to pass through proper apertures formed in the sills 11 and 14, this arrangement being best shown in Fig. 3.

85 From the construction described it will be seen that after removing the pins 7 the tail-board 24 may be removed by grasping the handles 27, pulling the board backward to free it from engagement with the irons 5, and then slightly lifting it to release the elongated heads of the bolts 2 from engagement with the mortises 4 of the cross-bar 13.

95 This cart, owing to its peculiar construction and the numerous metal facing-strips and the metal cross-bar at the rear of the cart, will 100

most effectively withstand the wear and tear due to the loading and unloading of minerals, coal, stone, or any other material that would be likely to wear or injure a cart constructed without the parts above referred to.

Having thus described my invention, what I claim as new, and desire to secure by Letters Patent, is—

1. A cart-body wherein the rear cross-bar consists of an iron bar which carries rectangular stay-irons, to which the sides of the cart are bolted, substantially as described.

2. A cart-body wherein the rear cross-bar consists of an iron bar formed with elongated slots or mortises adapted to receive extensions formed on the tail-board bolts, and wherein the side-boards are supported by triangular

stay-irons carried by the said iron cross-bar, substantially as described.

3. In a dump-cart, the combination, with a metallic rear cross-bar formed with mortises 4, of stay-irons bent to triangular form and bolted to the cross-bar, a tail-board provided with bolts 2, having elongated heads adapted to fit in the mortises 4, retaining-irons 5, and pins 7, substantially as described.

4. A tail-board for a cart-body, consisting, essentially, of a board to which there are secured facing-strips 25 and 26, and which is provided with bolts 2, substantially as described.

THOMAS JOHN FLANIGAN.
